US0D1084038S

(12) **United States Design Patent** (10) **Patent No.:** **US D1,084,038 S**
(45) **Date of Patent:** **** Jul. 15, 2025**

(54) **PORTABLE VACUUM PUMP**

(71) Applicant: **Zhuhai Cheer Technology Co., Ltd.,**
Guangdong (CN)

(72) Inventor: **Xiaoxian Song**, Guangdong (CN)

(**) Term: **15 Years**

(21) Appl. No.: **29/916,077**

(22) Filed: **Nov. 8, 2023**

(30) **Foreign Application Priority Data**

Oct. 11, 2023 (CN) 202330657051.1

CLAIM

The ornamental design for a portable vacuum pump, as shown and described.

DESCRIPTION

FIG. 1 is a front, top perspective view of a portable vacuum pump, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The dashed lines in the figures illustrate portions of the portable vacuum pump, that form no part of the claimed design.

1 Claim, 8 Drawing Sheets
